(57) **CLAIM**

The ornamental design for a hammock chair, as shown and described.

DESCRIPTION

FIG. 1 is a perspective view of a hammock chair showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of another state of the hammock chair thereof;

FIG. 9 is an enlarged view of the selected portion in FIG. 1; FIG. 10 is an enlarged view of the selected portion in FIG. 1; and,

FIG. 11 is an enlarged view of the selected portion in FIG. 1.

The broken lines shown in the drawings depict portions of the hammock chair in which the design is embodied that form no part of the claimed design.
